(57) **CLAIM**

The ornamental design for a vaginal speculum, as shown and described.

DESCRIPTION

FIG. 1 is a front perspective view of a vaginal speculum in accordance with a first embodiment of our design, the broken lines shown for illustrative purposes only and form no part of the claimed design;

FIG. 2 is a rear perspective view thereof;

FIG. 3 is a left side view thereof;

FIG. 4 is a front view thereof;

FIG. 5 is a rear view thereof;

FIG. 6 is a right side view thereof;

FIG. 7 is a top plan view thereof;

FIG. 8 is a bottom view thereof;

FIG. 9 is a front perspective view of a vaginal speculum in accordance with a second embodiment of our design, the broken lines shown for illustrative purposes only and form no part of the claimed design;

FIG. 10 is a rear perspective view thereof;

FIG. 11 is a left side view thereof;

FIG. 12 is a front view thereof;

FIG. 13 is a rear view thereof;

FIG. 14 is a right side view thereof;

FIG. 15 is a top plan view thereof; and,

FIG. 16 is a bottom view thereof.
